Specification for Design.

Patented Nov. 29, 1921.

Application filed June 30, 1921. Serial No. 481,667. Term of patent 14 years.

To all whom it may concern:

Be it known that I, JOHN J. FINUCANE, a citizen of the United States, residing at Rochester, in the county of Monroe and State of New York, have invented a new, original, and ornamental Design for Washing-Machines, of which the following is a specification and of which the accompanying drawing is a representation.

The figure is a perspective view of the washing machine, showing my new design.

I claim:

The ornamental design for a washing machine, as shown.

JOHN J. FINUCANE.
